UNITED STATES PATENT OFFICE.

WILLIAM NORDHOFF, OF BALTIMORE, MARYLAND, ASSIGNOR TO WM. KNABE & CO., OF SAME PLACE.

IMPROVEMENT IN PIANOS.

Specification forming part of Letters Patent No. 57,257, dated August 14, 1866.

To all whom it may concern:

Be it known that I, WILLIAM NORDHOFF, of Baltimore, in the county of Baltimore and State of Maryland, have invented certain new and useful Improvements in Piano-Fortes; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use the invention, I will proceed to describe it.

Figure 1 is a top-plan view of the frame of a piano with my improvement applied thereto. Fig. 2 is a transverse vertical section of the same, taken on the line $x x$ of Fig. 1.

It has long been known to the manufacturers of this class of instruments that the tone of the strings would be rendered far more pleasing if the agraffe could be secured to a plate of brass instead of iron; but there are two difficulties to overcome in doing this: First, a frame made entirely of brass is not only much more expensive, but is also too weak to stand the necessary strain upon the strings. Second, when a separate brass plate is used in connection with an iron frame it has been found almost or quite impossible by the methods heretofore used to so attach the brass plate to the wrest-plank as to render it secure, and at the same time prevent the vibration and rattle that was sure to follow between the iron and brass plates, whereby the tone of the instrument was greatly injured.

To overcome these difficulties is the object of my present invention, and the manner in which I accomplish it is as follows: I construct the wrest-plank C in the usual manner. I then form a brass plate, B, of the required size and form to fit the front of the wrest-plank, as shown in Fig. 1. This brass plate B is cast or otherwise made with two flanges standing at a right angle to each other, as shown in the cross-section, Fig. 2, one flange being let into the front edge of the plank C, while the horizontal flange is fitted into a recess cut for it in the top of the plank, as

shown clearly in Fig. 2, it being secured to the plank C by screws *o* passing through the vertical flange into the plank, while another series of screws, *n*, are inserted through the horizontal flange into the wood, as shown. The agraffes *e* are secured, in any suitable manner, to the upper front edge of this brass plate B, as shown in Fig. 2, the agraffes being either cast with the plate B or formed separately and then screwed into it, as may be preferred.

A represents the iron frame, to which the strings are secured in the usual manner. This frame is constructed with the bridge *a* upon its upper front surface, as shown, and is secured to the top of the wrest-plank C in such a manner as to cause its front portion to lap over and rest upon the brass plate B, as shown in Fig. 2. A series of screws, *b*, are inserted through its front edge, and, passing also through the brass plate B, enter the wood C, as shown, thereby uniting them all firmly together.

The string *t* is attached to the pin *p* in the usual manner, and passes thence over the bridge *a*, through the agraffe *e*, and across to the opposite end of the frame. It will be seen that any strain applied to the string *t* will tend to press down on the iron frame A, and at the same time will lift or pull upward on the plate B, whereby the two will be pressed and held together by the strain of the strings in a most perfect manner.

By this method of constructing and uniting the parts I am enabled to entirely obviate the difficulties heretofore mentioned and greatly improve the instrument.

Having thus described my invention, what I claim is—

The plate B, secured to the wrest-plate C, in combination with the frame A, when said parts are constructed and arranged to operate substantially as and for the purpose herein set forth.

WM. NORDHOFF.
